UNITED STATES PATENT OFFICE.

RUDOLF RICHTER, OF WILMERSDORF, NEAR BERLIN, GERMANY,
ASSIGNOR TO THE SIEMENS-SCHUCKERT WERKE G. M. B. H., OF
BERLIN, GERMANY, A CORPORATION OF GERMANY.

DEVICE FOR SINGLE-PHASE COLLECTOR-MOTORS WITH COMPENSATION-WIRING.

No. 831,101.

Specification of Letters Patent.

Patented Sept. 18, 1906.

Application filed November 21, 1905. Serial No. 288,390.

To all whom it may concern:

Be it known that I, RUDOLF RICHTER, engineer, a subject of the King of Prussia, German Emperor, and a resident of Wilmersdorf, near Berlin, Germany, have invented a certain new and useful Device for Single-Phase Collector-Motors with Compensation-Wiring, of which the following is a specification.

10 Commutator-motors are often provided with a compensating winding for neutralizing the transverse field produced by the armature-current, and in particular alternating-current motors are arranged in this manner 15 on well-known grounds.

The magnetomotive forces of the armature-winding and the compensation-winding are in this case equal and opposite. The compensating winding can in particular be so 20 arranged that between the poles of the machine at those places where the direction of the current in the coil is changed auxiliary fields are produced which allow this change to be effected without sparking at the brushes.

25 This auxiliary means is, however, as is well known, not sufficient in the case of alternating-current motors, as in the short-circuited coil an electromotive force occurs by transformation, in consequence of the pulsating 30 operative field, which is shifted one-quarter of a period relatively to the armature-current, and consequently cannot be neutralized by means of an auxiliary winding connected in series with the armature. For neutralizing 35 this electromotive force a transverse field is necessary, which (with two-pole motors) is shifted relatively to the main field both as to time and place by ninety degrees. For producing this auxiliary transverse field a phase 40 displacement may be produced between the armature-current and the compensating current. To effect this purpose, alternating-current motors have been constructed with short-circuited brushes, whose axis is placed 45 diagonally to the axis of the brushes connected to the external circuit. With these motors the phases of armature-current and compensation-current are no longer rigidly coupled by the definite conductive relation of 50 their circuits, as with the usual compensated single-phase motor, but only inductively. The currents are therefore subject to a certain phase shift relatively to each other, and

the resulting magnetomotive force gives the desired auxiliary transverse field.

55 The present invention relates to another means for effecting a phase shift between armature-current and compensation-current, which is applicable to the usual single-phase commutator-motor with compensation winding. The means consists in the use of a choking-coil, which is connected parallel to the armature. The armature of the compensated motor presents in working an ohmic resistance. The parallel connection of the 60 inductive resistance therefore has the effect that the entire main current no longer passes through the armature, but only the geometrical difference between the main current and the choking-coil current. The compensation 65 of the armature-current is then no longer complete, and there remains a resulting magnetomotive force which is proportional to the choking-coil current and is in phase with the same.

70 In the drawing I have shown a compensated single-phase motor in diagrammatic representation.

In said drawing, *a* indicates the armature, *p* the main field-poles, and *h* the compensation-winding, shown here in the form of the well-known auxiliary pole. *d* indicates a self-inductive resistance or choking-coil, which is connected in parallel with the armature *a*. In this way a transverse field of sufficient strength and of the right phase can be produced which will neutralize the electromotive force produced on the short-circuited coil by the pulsation of the main field. As in practice the phase shift required for the said 80 purpose between the armature-current and the compensation-current is relatively small, the above-described means is also practically useful. The choking-coil only has to carry a very small portion of the main current, and the loss of effect caused thereby is 85 exceedingly small. The choking-coil is of course advantageously so arranged that it allows of a regulation of the branched currents.

The described arrangement has the special 90 advantages that the amplitude of the auxiliary transverse field can be regulated at will independently of the other conditions, so that the motor can work free from sparking not only under synchronism, but also at all 95 speeds, and, furthermore, that it is applica- 100 105

ble to ordinary compensated motors without requiring other alterations therein.

The above-described invention is of course applicable also to motors whose compensation-winding is uniform, arranged for the production of auxiliary fields, which are intended to neutralize the reactance voltage in the short-circuited coil, as hereinbefore referred to.

Having now particularly described and ascertained the nature of my said invention and in what manner the same is to be performed, I declare that what I claim is—

1. In a single-phase commutator-motor, the combination with field and armature coils, and compensation-winding in series with the armature-coils; of a circuit in parallel with the armature and adapted to cooperate with the compensation-winding in neutralizing the cross-field of the armature.

2. A single-phase commutator-motor comprising field and armature coils, compensating coils in series with the armature, and a

choking-coil in parallel with the armature for the purpose set forth.

3. A single-phase commutator-motor with field and armature coils and compensation-winding in series with the armature, having a circuit in parallel with the armature to shift the phase of the current between the armature and compensation-winding.

4. A single-phase commutator-motor with compensating winding wherein the armature is provided with a parallel connected choking-coil for the purpose of effecting such a phase shift between the armature-current and the compensation-current as to produce a suitable transverse field in the armature for neutralizing the resulting electromotive force produced in the short-circuited coil, substantially as described.

RUDOLF RICHTER.
